THERMOSTATIC CONTROLLING DEVICE

James K. Lund, Oak Park, Ill., assignor to The Dole Valve Company, Chicago, Ill., a corporation of Illinois

Application May 7, 1937, Serial No. 141,330

4 Claims. (Cl. 236—34)

This invention relates to thermostatic controlling devices and has for its object to provide a new and improved device of this description. The invention has a further object to provide a thermostatic controlling device particularly adapted to be used in connection with the circulatory cooling systems of internal combustion engines.

The invention has as a further object to provide a thermostatic controlling device for the circulatory cooling system of an internal combustion engine wherein the function of pressure and temperature takes place below the casing flange.

The invention has further objects which are more particularly pointed out in the accompanying description.

Referring now to the drawing,

Fig. 1 is a view showing one form of device embodying the invention in position in the circulatory cooling system of an internal combustion engine;

Fig. 2 is an end view of the valve shown in Fig. 1; and

Fig. 3 is a sectional view taken on line 3—3 of Fig. 2.

Like numerals refer to like parts throughout the several figures.

Referring now to the drawing, I have illustrated a radiator 1 of an internal combustion engine, which is connected by a pipe 2 with the cooling jacket 3 of the internal combustion engine. Mounted in the connection between the cooling jacket 3 and the radiator 1 is a valve 4. This valve is provided with a casing 5 having at its upper end a laterally extending flange 6. This flange is preferably received between the end of the pipe 2 and the engine jacket 3, as shown in Fig. 1, and is clamped in position by means of the bolts 7. The flange 6 is at the upper end of the casing.

Pivotedly mounted in the casing is a valve 8, which is pivotally mounted at 9 in the casing, so that it may be moved to open and close it. A thermostatic device 10 has one end 11 connected with a fixed part 12 attached to the casing 5. The other end of the thermostatic device is connected with the valve 8. As herein shown, this connection is made by means of a link 13 to which one end of the thermostatic device is pivotally connected at 14. The other end of the link is pivotally connected at 15 with an enclosing housing 16 attached to the valve.

A baffle 17 is connected with the casing 5 above the valve and is inclined downwardly toward the valve and is normally separated from the valve

by a small space. The casing is provided with a bleed hole 18 located between the end of the valve when closed and the baffle 17. It will be noted that the baffle, and the valve, and the bleed hole, as well as the thermostatic device, are all located below the flange 6, so that the entire function of pressure and temperature takes place below the casing flange 6.

The use and operation of my invention are as follows.

When the valve is in position, as shown in Fig. 1, and the engine is started up, the engine is cool and the valve 8 is closed. The pressure due to the pump causes a certain amount of liquid to pass through the bleed hole 18 and between the baffle 17 and the valve 8 and up into the pipe above said valve and thence to the radiator. The parts are so constructed that the bleed hole liquid and the leakage around the valve should not be more than three gallons per minute.

The pressure on the lower side of the valve 8, due to the pump, tends to produce a friction on the pivots, which makes it more difficult for the thermostatic device to move the valve to open it. The liquid passing through the bleed hole to the other side of the valve tends in a small measure to reduce this friction at the very starting of the opening of the valve. When the valve starts to open, the liquid passing between the valve and the casing strikes the baffle 17 and is deflected by the baffle so as to strike the upper part of the valve 8 and tends to assist the thermostatic device in opening the valve. Since in this construction the baffle and the valve and the bleed hole and the thermostatic device are all below the flange 6 of the casing, they are all within the pressure and temperature area at all times and the entire function of pressure and temperature takes place below the casing flange. In this construction the liquid pressure referred to is the hydrostatic pressure head existing or caused to exist in the water jacket of the engine due to the water circulating pump. The liquid temperature is the temperature of the water surrounding or in the immediate vicinity of the thermostatic bimetal element, which acts thereon and which when it reaches a predetermined amount, causes the thermostatic element to move the valve.

The water jacket of the engine is the so-called high pressure chamber and the radiator and connection from the jacket beyond the valve is the so-called low pressure chamber of the cooling system. The pressure difference of the hydrostatic pressure existing in the so-called high and low pressure chambers of the cooling system de-

pends upon the amount of valve opening and the pump speed. When the thermostatic valve is fully open, the hydrostatic pressure between the two chambers is practically equalized and when 5 the thermostatic valve is fully closed, the hydrostatic pressure difference between these two chambers is a maximum. This maximum pressure condition creates a maximum friction on the valve shaft which must be overcome before 10 the valve will start to open. This inherently means the start to open temperature of the thermostat will vary with the pressure conditions. Hence to improve the opening performance of the thermostat means for neutralizing 15 or compensating for shaft friction must be incorporated to function automatically with changes in pressure, so as to permit the valve to open at substantially the same temperature, regardless of pressure. The dynamic force of the 20 liquid passing through the bleed hole and impinging on the valve accomplishes this result in an automatic manner. The greater the hydrostatic pressure, the greater is the dynamic force of the liquid impinging upon the valve. 25 This makes it possible to provide a construction which is more efficient, more adaptable and produces more satisfactory results than has heretofore been possible with valves of this type, and this is particularly true in connection with 30 circulatory cooling systems which have comparatively high pressures. This construction also permits the radiator and connections to be filled with the cooling liquid before the engine temperature is reached which causes the opening of 35 the valve.

I claim:

1. A thermostatic controlling device for the circulatory cooling systems of internal combustion engines, having a high pressure chamber and a 40 low pressure chamber, comprising a casing, a flange for said casing by means of which it is held in position, a valve pivoted in said casing for controlling the passage of liquid through the casing, a baffle attached to said casing above said 45 valve, an opening in the casing below the baffle and above said valve, and a thermostatic device connected with said valve so as to move it when the temperature reaches a predetermined point, to open the valve, said valve casing being located 50 in the high pressure chamber, said opening communicating with the high pressure chamber and the space between said baffle and the face of the valve in the low pressure chamber, so that the pressure in the high pressure chamber is utilized 55 to assist the thermostat in opening the valve.
2. A thermostatic controlling device for the circulatory cooling systems of internal combustion engines, having a high pressure chamber

and a low pressure chamber, comprising a casing, a valve pivotally mounted in said casing for controlling the passage of liquid through the casing, a baffle on the interior of said casing above said valve, an opening in the casing below the baffle and above said valve, a thermostatic device connected with said valve so as to move it when the temperature reaches a predetermined point, and means for fastening said casing in the circulatory system of the engine, so that the said baffle, opening, valve and thermostatic device are at all times subjected to the pressures and temperatures in the engine cooling jacket, said opening communicating with the high pressure chamber and the 15 space between said baffle and the face of the valve in the low pressure chamber, so that the pressure in the high pressure chamber is utilized to assist the thermostat in opening the valve, whereby the valve is opened at substantially the 20 temperature for which the thermostat is set, regardless of the pressure in the high pressure chamber.

3. A thermostatic controlling device for the circulatory cooling systems of internal combustion engines, having a low pressure chamber and a high pressure chamber comprising a casing, a valve pivotally mounted in said casing, a baffle on the interior of said casing above said valve, an opening in the casing intermediate the baffle and 25 the valve, a thermostatic device connected with said valve so as to move it when the temperature reaches a predetermined point, the portion of the casing containing the baffle, opening, and valve being located in the high pressure chamber, said opening connecting the space between the baffle and the face of the valve in the low pressure chamber with the high pressure chamber, so that variations in pressure in the high pressure chamber are automatically utilized to 30 provide an opening pressure on the valve, whereby the valve is opened at substantially the temperature for which the thermostat is set, regardless of the pressure in the high pressure chamber.

4. A thermostatic controlling device for the circulatory cooling system of an internal combustion engine having a high pressure area and a low pressure area when the engine is started up cold, comprising a valve which separates the low 35 pressure area from the high pressure area when closed, a thermostat for opening said valve, and means in said high pressure area for applying the pressure in the high pressure area to the low pressure side of said valve when it is closed and 40 before it starts to open.

JAMES K. LUND.
